(57) **CLAIM**

The ornamental design for a wall-assisted floor mount for a monitoring camera, as shown and described.

DESCRIPTION

FIG. 1 is a top, front, left-side perspective view of a wall-assisted floor mount for a monitoring camera showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines, the areas within the broken lines, and the areas enclosed by both broken lines and solid lines adjacent to shaded areas depict portions of the wall-assisted floor mount for a monitoring camera that form no part of the claimed design.
